UNITED STATES PATENT OFFICE.

GEORGE W. DAGGETT, OF NORTH GIRARD, PENNSYLVANIA.

LIGHTING SYSTEM.

1,415,159.

Specification of Letters Patent. Patented May 9, 1922.

Application filed December 22, 1915. Serial No. 68,292.

To all whom it may concern:

Be it known that I, GEORGE W. DAGGETT, a citizen of the United States, residing at North Girard, in the county of Erie and State of Pennsylvania, have invented new and useful Improvements in Lighting Systems, of which the following is a specification.

This invention relates to lighting systems and consists in certain improvements in the construction thereof as will be hereinafter fully described and pointed out in the claims.

More particularly the invention relates to these lighting units which involve the use of an explosive engine and has for its object the simplifying of such mechanisms and rendering the same more nearly automatic in their operation.

The invention is illustrated in the accompanying drawings wherein 1 marks the explosive engine, 2 a lighting generator, 3 a charging generator and starting motor, 4 a magneto for the engine, 5 a storage battery and 6 a light. The magneto may be dispensed with and the ignition accomplished either from the storage battery or a separate supply and the charging generator and starting motor 3 may be formed in separate units or may be combined.

With the lighting systems of common use it is the usual practice to charge the battery and use the current directly from the battery or in connection with that going to the battery and where a high voltage system is used this requires a very large and expensive battery. On the other hand, it does not require the constant running of the engine. Another system is to permit the engine to run continuously. With this system a very small battery, if any, is required. With the present system it is proposed to use a small battery simply large enough for operating the starting motor preferably at low voltage and to automatically start the engine at any time a switch is turned on and a light. In carrying out the system as soon as the switch is turned on, the ignition system is connected up, the engine is started, the lighting circuit connected, the starting circuit disconnected and the charging circuit connected so that as the engine runs the storage battery is charged. On opening the switch at the light the ignition system is opened, stopping the engine and the connection to the storage battery is opened.

The light 6 is between the wires 7 and 8.

The wire 8 has the switch 9, ordinarily the socket switch by which the light is turned on and off. The wire 8 runs to a coil 10 and from the coil 10 by a wire 11, wire 12 to a coil 13, from the coil 13 by the wire 14 to the switch 15, thence by wires 16 and 17 to the battery 5. It will be readily seen that as the switch 9 is closed, current from the battery 5 will flow through the coils 10 and 13. The coil 10 operating on the plate 18 overcomes the spring 19 which normally holds the plate outwardly so as to close a connection between the wires 20 and 21. The wires 20 and 21 lead to the magneto 4. As soon as the switch formed by the plate 18 is opened, the magneto circuit leads to the ground 23 at one side and by way of the wire 24 which connects with the wire 21 to the spark plug 25 at the other side of the engine forming a ground at the other side of the circuit so that the ignition system is connected up. The coil 13 attracts the plate 26 and overcoming the spring 27 closes a switch in the wire 28. The wire 28 leads to a wire 28^a and the wire 28^a to one side of the starting motor by way of the wires 29 and 17 to the storage battery. The opposite side of the starting motor 3 is connected by way of the wire 30 with the wire 7 leading to the storage battery. Thus as soon as the switch 9 is closed and current supplied to the coil 13 the circuit between the battery and the starting motor is closed thus starting the engine. As soon as the engine starts, current is developed in the lighting generator 2. A wire 31 leads from one side of this generator to the wire 11 and thence to the wire 8 as heretofore traced. The opposite side of the generator leads through the wire 32, wire 33, coil 34 and wire 35 back to the wire 31 forming a circuit through the coil 34. As soon as the current is sufficiently developed to overcome the spring 34, the switch lever 36 is moved, opening the switch 15 and closing the switch 37. The switch 37 closes a connection between the wire 32 and the wire 7 so that there is a lighting circuit by way of the wires 31, 11, 8, 7 and 32. There is sufficient resistance in the coil 34 to prevent an undue amount of current passing through this coil. At the same time, there is sufficient while the lighting generator is in operation to hold the lever 36 in position to close the switch 37.

The opening of the switch 15 breaks the circuit through the coil 13 and the switch

plate 26 is retracted by the spring 27 thus breaking the circuit between the storage battery and the starting motor. The movement of the switch lever 36 closes a switch 39. A wire 40 leads to the wire 28 and thus to one side of the starting motor and charging generator 3. The wire 38 leads from the other side of the switch 39 to the wire 29 and thence by the wires 29 and 17 to the storage battery. The connection with the generator 3 is retained through the wires 30 and 7 to the storage battery. Thus during the running of the engine and after current is in the lighting circuit, connection is made whereby the generator 3 charges the battery. It will be understood that the lighting circuit is comparatively high voltage, ordinarily about 110, whereas the battery circuit is low voltage, ordinarily about 20 six volts.

Upon the opening of the switch 9 the spring retracts the switch plate 18 and short circuits the magneto through the wires 20 and 21 thus stopping the engine. This cuts off the current from the light circuit and the spring 34 immediately retracts the switch lever 36 opening the switches 37 and 39 closing the switch 15, the switch 9 being open, however, the circuit by way of the switch 15 is open. This leaves the parts in position of rest and ready to be brought into action at any time by the closing of the switch 9 so as to turn on the light.

The present system, as before stated, permits of the use of a very small storage battery and still requires the running of the engine only when light is required. At the same time the turning on of a light in the lighting circuit will put the system automatically into operation.

What I claim as new is:—

1. In an electric system of the character described, the combination of an engine, a starting motor and charging generator, a generator, mechanical driving connections from said engine to said starting motor and charging generator and said generator, a storage battery, leads normally connected to said battery when said engine is not running, means for connecting said battery to said starting motor and charging generator to start said engine when said battery delivers current to said leads, and means re-

sponsive to the engine speed for opening the circuit between said battery and said leads and closing the circuit between said generator and said leads and effecting connection between the starting motor and charging generator and the battery during the operation of the engine. 60

2. In a lighting system, the combination of an explosive engine; a lighting generator; a storage battery; a starting motor and charging generator connected with said engine and said battery; a lighting circuit connected with the lighting generator; a starting circuit connected into the lighting circuit; a manually actuated switch in the lighting circuit and adapted to cause to be closed initially the starting circuit; a starting switch in said starting circuit; an ignition system; devices actuated by current in the starting circuit for connecting the starting motor and charging generator with the battery; a lighting switch connecting the lighting generator with the lighting circuit; and means energized by the lighting generator for opening the starting switch and closing the lighting switch. 70

3. In a lighting system, the combination of an explosive engine; a lighting generator; a storage battery; a starting motor and charging generator connected with said engine and said battery; a lighting circuit connected with the lighting generator; a starting circuit connected into the lighting circuit; a manually actuated switch in the lighting circuit and adapted to cause to be closed initially the starting circuit; a starting switch in said starting circuit; an ignition system; devices actuated by current in the starting circuit for connecting the starting motor and charging generator with the battery; a lighting switch connecting the lighting generator with the lighting circuit, a charging switch controlling the connection between the starting motor and charging generator and the battery; and means energized by the lighting generator for opening the starting switch and closing the lighting and charging switches. 90

In testimony whereof I have hereunto set my hand.

GEORGE W. DAGGETT.
